UNITED STATES PATENT OFFICE.

JUSTIN KAY TOLES, OF BERKELEY, CALIFORNIA.

COMBINED CONTAINER AND CUTTER.

1,026,778.

Specification of Letters Patent. > Patented May 21, 1912.

Application filed December 8, 1910, Serial No. 596,232. Renewed March 4, 1912. Serial No. 681,657.

To all whom it may concern:

Be it known that I, JUSTIN KAY TOLES, a citizen of the United States of America, residing at Berkeley, in the county of Alameda, State of California, have invented a certain new and useful Combined Container and Cutter; and I do hereby declare the following to be a full, clear, and exact description of the invention, such as will enable others skilled in the art to which it appertains to make and use the same.

This invention relates to a combined container and cutter, and it may be said to consist in the novel construction, arrangement and combination of the parts as will appear from the description and claims hereinafter.

One object of the invention is to provide a device of the class specified in which a cutter is conveniently arranged in a novel manner and adapted to act effectively to sever a strip of adhesive plaster or tape, or the like, unwound from a coil thereof disposed within the container.

Another object of the invention is to provide means for revolvably mounting the coil within the container.

Still another object of the invention is to provide a novel construction whereby the end portions of the coil may always be in a condition to be easily grasped by the fingers.

Other objects and the advantages of the invention will be apparent to those skilled in the art from a consideration of the following description of the preferred form of construction in which the invention may be embodied, taken in connection with the accompanying drawings in which,

Figure 1 is a perspective view of a container with the cover shown detached in order to show the interior parts; Fig. 2 is a perspective view of the above with the cutter in the operative position.

The container 2 may preferably consist of the heads 3 and 4 and the cylindrical body 5, which latter is preferably provided with a slot 6 therein. Each of the heads is, by suitably crimping the material thereof, provided with an annular groove 7 into which edges of the body 5 may fit; the parts being held together by a central spindle 9 passing through a hole 10 in the heads and buried over at each end. The heads 3 and 4 may be formed to provide, adjacent to slot

6, guides 11 in which is adapted to slide the curved cutter 12. The cutter is desirably provided with a fingerpiece 13 whereby it may be moved either to cover or uncover slot 6, or to a position forwardly of the slot. Adjacent to slot 6 the material of body 5 may be inwardly deflected to form a depression 15 over which the cutting edge 14 of the cutter is positioned in operation. Upon the spindle 9 may be revolvably mounted on a sleeve 8 a coil of adhesive plaster, or tape, or the like, the outer end 16 of which may be brought upwardly through the slot 6 and pressed down on the lip 17 on the cylindrical body 5 adjacent to depression 15.

In operation, the end portion of the tape or adhesive plaster positioned above depression 15 may be grasped by the fingers and pulled from lip 17 and as much of the plaster or tape as desired may be unwound from the coil 9. Cutter 12 may then be moved over slot 6 until its cutting edge 14 is in position over the depression 15, causing the end 16 of the plaster or tape to be pressed upon and made to adhere to lip 17. The free end of the plaster or tape may then be drawn diagonally backward over the edge 14 of the cutter 12 and thus severed. It will be seen that at every operation the end portion of the plaster or tape is left adhering to the lip 17 thus presenting a free end of the plaster or tape projecting over said depression 15.

While one form of construction in which the invention may be embodied has been illustrated and described, various changes and modifications thereof will readily occur to those skilled in the art, and the right is therefore reserved to all such changes and modifications as do not depart from the spirit and scope of the invention.

I claim:

1. In a device of the class specified, the combination of a container provided with a slot therein and guides adjacent to said slot, a spindle in the container, a sleeve loosely mounted on the spindle and adapted to carry a coil of adhesive plaster thereon, and a cutter arranged movably in said guides.

2. In a device of the class specified, the combination of a container having guides formed thereon, said container provided with a slot therein and having a lip and a depression adjacent to said slot, means per-

mitting rotation of a coil of adhesive plaster disposed within said container, and a cutter arranged movably in said guides on said container adjacent to said slot, substantially 5 as described.

In testimony whereof, I have signed my name to this specification in the presence of

two subscribing witnesses at Los Angeles, county of Los Angeles, State of California, this 3rd day of December A. D. 1910.

JUSTIN KAY TOLES.
